RELEASING DEVICE FOR LOCKING PLIERS

Homer A. Mead, Turlock, Calif.

Application October 3, 1952, Serial No. 312,913

4 Claims. (Cl. 81—84)

1

This invention relates to self-locking wrench-pliers of that type so constructed that the jaw connecting linkage moves past dead center when the jaws tightly grip a piece of work, and locks said jaws against release.

The major object of this invention is to provide a simple and efficient device mounted on the pliers and operable by a finger of the hand grasping the pliers, for breaking the dead center lock so that the jaws and their controlling handles may be opened or spread without substantial resistance.

A further object is to provide a device, for the purpose, arranged to exert a great releasing force—on the parts to be released—with a minimum of finger pressure; the device working smoothly, positively, and quickly.

Such device includes a finger lever, and another object of the invention is to arrange this lever so that it is in a position most convenient and natural for operation by a finger of the hand holding the pliers; the lever having a minimum of projection when in its normal position.

A further object of the invention is to provide a releasing device, for locking pliers, which is designed for ease and economy of manufacture.

A still further object of the invention is to provide a practical and reliable releasing device for locking pliers, and a device which is exceedingly effective for the purpose for which it is designed.

These objects are accomplished by means of such structure and relative arrangement of parts as will fully appear by a perusal of the following specification and claims.

In the drawings:

Fig. 1 is a side elevation of the pliers with the jaws spread to straddle a piece of work such as a nut, before engaging the same.

Fig. 2 is a similar view, partly broken out and in section, showing the jaws of the pliers gripping the work locked against release.

Fig. 3 is a similar view, but with the lock released by actuation of the finger lever.

Fig. 4 is a fragmentary cross section on line 4—4 of Fig. 2.

Fig. 5 is a fragmentary transverse section on line 5—5 of Fig. 1.

Referring now more particularly to the characters of reference on the drawings, the pliers comprises stationary and movable jaws 1 and 2, respectively; jaw 1 being rigid with a straight elongated handle 3, which is of deep U-shaped form in section, with the opening of the U facing away from the outer edge of the handle as plainly shown in Fig. 4.

2

The jaw 2 is formed with a shank 4 projecting at an angle to said jaw and between the sides 5 of handle 3, the shank being pivoted to said sides a relatively short distance below jaw 1 by a pin 6.

5 A handle 7, also of deep U-form in cross section to provide spaced sides 8 and opening in the direction of handle 3, is pivoted at its forward end by a pin 9 on shank 4 adjacent its outer side at a point generally opposite pivot 6.

10 The handles are connected by a rigid toggle link 10 which includes a forward portion 11 of rectangular cross section to fit closely between the sides 8 and 5 of the handles and a rearward threaded portion 12 fitting in clearance relation 15 between the sides 5 of handle 1.

The link extends diagonally of the handles and is pivoted at its forward end on the handles sides 8 by a cross pin 13 disposed some distance rearwardly of pivot 9 and clear of jaw shank 4.

20 A knurled finger nut 14 of greater diameter than the outside width of handle 3 is threaded on link portion 12. The nut is confined in the sides 5 of handle 3 by and projects through cage-forming openings 15 cut through said walls. The

25 bottom walls of the openings are shaped to form transversely aligned fulcrum points 16 engaging and about which the nut may rock; the inner side and forward walls of the openings being curved, as at 17, about said fulcrum points as an axis and confining the nut without restricting its rotation.

30 This enables the link and nut to swing as a unit about the fulcrums 16 without material friction as handle 7 is swung to open and close the movable jaw 2 relative to the fixed jaw 1. The openings, however, are elongated at their outer side as shown at 15a for the initial insertion of the nut 14.

35 The pivot 13 is disposed relative to a line 18 drawn through the fulcrum point 16 and the axis of pivot 9 so that pin 13 is disposed laterally in from said line when the handles are brought together with the jaws tightly gripped with a piece of work such as a nut N, as shown in Fig. 2.

40 The jaws are thus locked against being opened by any pressure exerted on the jaws at the work, and in order to break the lock in a simple and convenient manner, the following arrangement is provided:

Pivoted, as at 19, between the sides 8 of handle 7 and rearwardly of pin 13 is a finger lever 20 which projects through a longitudinal slot 21 formed in the back of the handle 7 and is shaped at its end outwardly of the handle as a curved actuating tip 22.

55 The inner end of the lever 20 is curved eccen-

tric to the axis of pivot 19 to provide a cam face 23 disposed so that the distance from the cam face to said pivot increases rearwardly. The link 10 is disposed so as to be engaged by the cam face 23 when the handles are closed. In order to enable the lever 20 to be as long as possible and still project but little from the back of the handle, the portion 11 of the link 10 is formed as a dog leg bent away from the finger lever, the outer edge or face 24 of the portion 11 rearwardly of the bend being that engaged by and disposed at a considerable angle to said cam face. It may here be noted that the threaded portion 12 is not affected by the shape of portion 11, and said threaded portion remains radially disposed relative to pin 13.

The lever 20, in its inoperative position is disposed at the upper end of slot 21, being yieldably held in that position by a leaf spring 25 pressed at its lower end into a notch 26 cut in the upper side of the lever 20 back from the pivot, and extending thence forwardly to slidably bear against back of the handle 7 inside the same and ahead of the slot.

The eccentric face 23 is so related to pivot 19 and to the link face 24 that as the cam is rotated, by pulling rearward on lever 20, said face rolls on or walks easily along face 24 without slipping or appreciable friction, and hence a greater and more positive cam pressure can be exerted on link 10. Also, wear on the contacting faces is reduced to a minimum and practically eliminated.

With this arrangement, therefore, and with the link locked past dead center, it is only necessary to pull lever 20 rearward, as shown in Fig. 3. Because of the eccentric relation of cam face 23 to pivot 19 and face 24, this causes the handle 7 to be swung out relative to handle 3, the cam rolling on link face 24 without slipping, as described. This handle movement is, of course, accompanied by an outward movement of link pivot 13, the link swinging about the fulcrum points 16.

Also, because of the above described eccentric cam face arrangement, a relatively slow but very great leverage is exerted at the outset of the lock-breaking operation, when it is most needed, while a lesser leverage and faster movement occurs toward completion of such operation, as is also desirable. Additionally, the relatively great length of lever 20, made possible by the dog-leg or recessed form of the upper portion of the link 10, enables the desired action to be obtained with a minimum of finger pull.

It is to be further noted that lever 20 normally extends at a forward diagonal from pivot 19 so that the tip 22 is initially ahead of said pivot 19, while the eccentric cam face 23 is rearwardly of such pivot. This arrangement of parts is advantageous, as the finger imparted motion of tip 22, required to release the pliers, is rearward as distinguished from laterally inward whereby the releasing force does not oppose or work against the opening movement of the handle 7.

From the foregoing description, it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent is desired:

1. In wrench type pliers including relatively movable handles and a beyond dead center locking unit connected diagonally between said handles, the movable handle being channel shaped and opening inwardly; a releasing unit comprising a lever extending laterally of the pliers and disposed mainly in the channel of the movable handle with its inner end adjacent the locking unit, said movable handle having a longitudinal slot through which the outer end of the lever projects, a cross pin pivoting the lever adjacent its inner end on said handle, and a cam on the inner end of the lever engaging the locking unit and arranged to impart a releasing movement to said locking unit upon actuation of the lever and movement of the outer end thereof in a direction away from the jaws.

2. A pliers as in claim 1, in which the cam is disposed close to the pivot pin and is arranged relative thereto to exert the greatest leverage against the locking unit at the inception of the actuating movement of the lever and to roll upon the unit with movement of the lever about the pivot pin; the lever when in its initial position being disposed at an acute angle to the locking unit in the direction of the jaws so that the outer end of the lever is then closer to the jaw end of the pliers than the pivot of the lever.

3. A pliers as in claim 1, in which the cam is disposed close to the pivot pin and is arranged relative thereto to exert the greatest leverage against the locking unit at the inception of the actuating movement of the lever and to roll upon the unit with movement of the lever about the pivot pin; said point of greatest leverage of the cam being substantially on a line drawn through the pivot pin and the outer end of the lever.

4. A pliers as in claim 1 in which the locking unit includes a link against which the cam bears; said link being deflected inwardly intermediate its ends and away from a straight line drawn through said deflected portion of the link.

HOMER A. MEAD.
